UNITED STATES PATENT OFFICE

RICHARD J. WILKINSON, OF PAWTUCKET, RHODE ISLAND, ASSIGNOR TO RIBELASTIC COMPANY, OF NEEDHAM HEIGHTS, MASSACHUSETTS, A CORPORATION OF MASSACHUSETTS

KNITTING ELASTIC FABRICS

Application filed October 7, 1927. Serial No. 224,691.

This invention relates to methods and apparatus for knitting seamless tubular elastic fabrics of the type characterized by having a knitted body of yarn with courses of elastic 5 rubber thread inlaid in some of the yarn courses.

The invention is particularly directed to the manufacture of a knitted garment having courses of elastic rubber thread inlaid with 10 certain of the yarn courses and with the elasticity of the rubber thread courses varied at predetermined locations along the length of the garment to provide varying degrees of elasticity and stretch of the garment and with 15 the garment shaped to conform with the body of the wearer or having different and variable diameters along its length; and one of the objects of this invention is a method and apparatus for manufacturing this garment.

20 A further object of the invention is the provision of a circular knitting machine adapted to make tubular knitted fabrics of yarn with means to inlay an elastic rubber thread in certain of the yarn courses of the fabric as 25 the knitting progresses, and means to vary the tension on the elastic rubber thread as it is inlaid in the fabric whereby to vary the stretch of the fabric and also to shape the fabric.

30 Another object of the invention is the provision of a circular knitting machine adapted for the inlaying of an elastic rubber thread in the yarn courses of the fabric with means to vary the tension of the elastic rubber thread 35 automatically in accordance with a predetermined pattern, whereby to shape the knitted garment.

A yet further object of the invention is the provision of an elastic thread feeding and 40 variable tension mechanism adapted as an attachment to be applied to existing knitting machines.

Another object of the invention is the provision of a circular knitting machine arranged for the inlaying of an elastic rubber thread in but one course of a predetermined 45 number of courses, as in every other course, or in every fourth course and the like.

A yet further object of the invention is the 50 provision of a circular knitting machine hav-

ing a plurality of yarn feeds with means to inlay in the yarn courses the same number or a lesser number of rubber thread courses, whereby greatly to accelerate the speed of manufacture of the elastic fabric.

A yet further object of the invention is generally to improve upon methods and apparatus for the manufacture of knitted elastic fabrics, the elasticity of which is provided by 55 courses of elastic thread inlaid with the yarn 60 courses.

Fig. 1 is a side elevation of a circular knitting machine embodying this invention, the bobbin frame support not being shown.

Fig. 2 is a plan view of the machine of 65 Fig. 1.

Fig. 3 is a plan view of the variable tension elastic thread feeding mechanism embodying the invention.

Fig. 4 is a side elevation of the mechanism 70 of Fig. 1 taken along line 4-4 of Fig. 2.

Fig. 5 is an end view of the thread feeding mechanism removed from the knitting machine.

Fig. 6 is a modified arrangement of the 75 elastic thread feeding mechanism wherein the tension of the thread is adapted to be adjusted by hand.

Fig. 7 is a plan view showing the modified 80 guide for the elastic thread used in the mechanism of Fig. 6.

Fig. 8 is a front view of the tension adjusting mechanism for the feed mechanism.

Fig. 9 is a side view of the tension mechanism of Fig. 8.

Fig. 10 is a plan view of the pattern plate 85 of the tension mechanism.

Fig. 11 is a view of the tubular knitted elastic garment adapted to be made by the 90 mechanism herein described.

Fig. 12 is a side elevation of the machine and illustrating particularly the manner of extending the elastic rubber thread from the stationary can to the feed and tension mechanism.

The apparatus here shown is adapted especially to knit the elastic garment illustrated in Fig. 11, although it is not limited to the manufacture of such garment since the shape 100

and dimensions of the product of the machine can be varied practically at will.

The garment shown in Fig. 11 is a so-called combined girdle and brassière which is integral, tubular and seamless and has courses of elastic thread inlaid in certain of the yarn courses, with the tension of the elastic thread courses varied in certain parts of the garment to provide the shape and stretch desired.

As shown in Fig. 11, the garment is large at the hips *a*, is smaller at the bottom *b*, contracts gradually to the waist *c*, and gradually enlarges to the bust portion *d* and may again contract to the top *e*. The shape is provided by varying the elasticity of the rubber thread along the length of the garment; and the brassière portion of the garment or that portion from *e* to *c* may have a lighter rubber than in the girdle portion, or that portion from *c* to *b*.

The circular knitting machine adapted for the making of this garment comprises a stationary cam ring 20 supported on housing plates 22 from a bed plate 24 which in turn is supported on legs 26. The knitting machine has the usual rotary needle cylinder 28 which rotates within the stationary cam ring and has a cylinder gear 30 which meshes with a bevel gear 32 carried by the drive shaft 34 by which the needle cylinder may be rotated. The machine has the usual dial plate 36 disposed immediately above the needle cylinder and under the dial cap 38 which is supported from and beneath the dial arch 40, which arch is carried by studs 42 from the cam ring 20.

The yarn is held in bobbins disposed above the machine on a bobbin frame support 44 which is broken away in Fig. 1 and the yarn passes downwardly and through yarn guides or carriers 46, Fig. 2, and thence to the needles of the dial and cylinder. The machine here shown is adapted for four yarn feeds and thus knits four yarn courses for each revolution of the cylinder. The machine so far described is common in the art.

In accordance with this invention, provision is made for feeding elastic rubber thread into certain of the yarn courses and for varying the tension of the rubber thread as may be desired. As here shown, the machine is arranged to feed elastic rubber thread into every other yarn course and to this end is provided with means to feed two rubber threads at opposite sides of the cylinder and adjacent two opposite yarn guides or carriers 46 and at the point where the stitch is made. The elastic rubber thread feeding and tension mechanism for both yarn threads are or may be identical and but one will be described.

Said feeding mechanism is shown most specifically in Figs. 3, 4 and 5. The mechanism includes a supporting frame having the hori-

zontal foot 48 which is supported upon the cam ring 20 adjacent the needle cylinder and also adjacent one of the yarn guides 46. Said foot is provided with a slot 50 therein in which an attaching bolt 52, Fig. 2, threaded in the cam ring 20 is passed whereby to secure the bracket in properly adjusted radial relation with the needle cylinder. The bracket includes a vertical support 54. An arm 56 is disposed upon the top of said support and is fixed detachably thereto by a screw 58 which is passed through said arm and is screw threaded into said support. A vertical shaft 60 is journaled in and extends upwardly above said arm and carries a thread driving cone 62 which is fixed detachably to said shaft by the pin 64. Said cone preferably is of metal and has a knurled outer surface and is large at the top and small at the bottom. A gear 66 is fixed to the lower end of said shaft 60 below said arm 56 and is arranged in mesh with the needles 68 in the needle cylinder 28, so that as said needle cylinder is rotated, the needles are caused to drive said gear 66 and the driving cone 62. A second arm 70 is pivoted on said vertical support 54 beside said fixed arm 56 by a pivot pin 72 which passes through said arm 70 and into said support 54. A vertical shaft 74 is fixed in the end of said arm and an idler cone 76 is journaled thereon and is disposed in cooperating relation with said driving cone. Said cone 76 preferably is similar to the driving cone 62 in that it has the same dimensions and is of metal and has a knurled outer face. Said cone 76, however, is large at the bottom and small at the top. The elastic rubber thread is adapted to be fed from a suitable source, not shown, through the bite of the cones and thence to the needles. An arm 78 is fixed to the side of the vertical support 54 and overlies the pivoted arm 70 and has an adjusting screw 80 therein which is adapted to bear against the pivoted arm 70 to adjust the position of the idler cone with respect to the driving cone and thus to adjust the pressure of the cones on the elastic rubber thread.

It is apparent that the point of engagement of the elastic rubber thread on the driving cone determines the speed of feed of the rubber thread to the rotary needles and consequently the tension on the thread. For instance, if the rotary needles move 10" while the cones feed 4" of rubber thread, the rubber thread must be stretched out to 10" which consequently gives a six inch stretch to the rubber and, when the goods are free and the rubber thread can come to a "knitted" ease, the goods are contracted by an amount set by the stretch of the rubber thread. If the thread engages the driving cone 62 near the large end, the speed of feed will be relatively great and consequently the rubber thread will be under little tension and the fabric will be

large in diameter. When the rubber thread engages the driving cone near the small end, the speed of feed of the rubber thread will be relatively slow so that the rubber thread will be fed to the needles under strong tension and, consequently, will pull in the garment so that it will have reduced diameter. By varying the location of the thread up or down the cone, the tension of the thread as it is fed to the needles can be varied and consequently the shape of the tubular fabric can be varied. The elastic rubber thread T is guided into the bite of the cones through the tubular guide or carrier 82. Said carrier has a depending flat bar 84 which is slidable in a correspondingly formed vertical slot provided in the plate 86 attached to the front face of the support 54. As thus arranged, the carrier is free for vertical movements and can occupy any selected position between the ends of the cones, thus to vary the tension of the elastic thread. When the tension of the elastic thread is to be maintained practically constant as for knitting straight tubular elastic goods, the guide 82^a, see Fig. 6, can be moved vertically by the adjusting screw 88, which is screw threaded into said carrier and bears against the arm 56, into some position which gives the proper tension 30 of the elastic thread and then left in such position until it is required to change the tension of the thread. The garment, however, can be shaped by manually rotating the adjusting screw 88 as the knitting of the garment progresses and in a manner indicated by the pattern desired, thus to shape the goods. This manual adjustment can not be depended upon to produce duplicate shaped goods however and furthermore requires the constant attendance of an operative.

The elastic thread in the construction shown in Fig. 4 passes through the cones and thence downwardly through a passage in a thread guide 90 which is carried by the support 54 and is disposed above the top of the needle cylinder. If desired, the thread guide 82^a may be provided with a guide arm 82^b, Fig. 6, which has a thread passage 82^c arranged about in horizontal line with the thread passage in the guide 82^a through which the thread passes downwardly into the guide 90. This arrangement serves to guide the thread in a horizontal direction into and out of the feed cones and under some conditions may serve to maintain a more accurate tension on the elastic thread than with the construction shown in Fig. 4. Ordinarily, however, it is found unnecessary to use the forward guide 82^b.

In accordance with this invention, means are provided to vary the tension of the elastic rubber thread automatically in accordance with a predetermined pattern and to this end tension adjusting means is arranged to move the guide 82 vertically in accordance with the

predetermined pattern whereby to position the rubber thread in driving engagement with the driving cone at suitable diameters thereof. To this end, the bar 84 of the thread guide 82 is pivotally connected through a screw 92 with the upper end of a vertically extended link 94, see Figs. 1, 4, 8 and 9. The lower end of said link is pivotally connected with the one end of a lever 96 that is pivotally connected intermediate its ends on a pin 98 passed through an upstanding plate 100 carried by a bracket or frame 102 secured to the edge of the cam ring 20. Said lever 96 is provided with a plurality of longitudinally-spaced pin-receiving apertures 104 and said plate 100 is provided with a plurality of horizontally-extended pin-receiving apertures 106. The pin 98 is adapted to be inserted in any two of said apertures 106 and 104 that may be brought into alignment whereby to adjust the throw of the lever and consequently the extent of vertical movement of the guide 82. Said lever is reciprocated by a shaft 108 rotatable in spaced brackets 110. An arm 112 is fixed to the inner end of said shaft 108 and has a pin 114 extended from the end thereof which operates in a longitudinal slot 116 of said lever 96. An arm 118 is clamped adjustably to the outer end of said shaft 108 and has a longitudinally extended rod 120 received detachably in an aperture in the lower end thereof. Said rod is provided with a roller 122 at its free end which is adapted to engage and ride over a cam profile carried by a pattern disc 124. Said pattern disc is shown most clearly in Figs. 9 and 10, and comprises a circular disc provided with a series of screw threaded apertures 126 in one face thereof. Screws 128 are adapted to be received in certain of said apertures to project in the same direction from the face of the disc as shown in Fig. 9 to form an adjustable cam profile; and the screws are placed in such apertures 126 that the cam profile will be of the shape desired. The shape shown in Fig. 10 is approximately the shape required to form two of the garments shown in Fig. 11, the opposite and highest ends of the cam profile following a circular curve knitting the ends or welts of the garments under constant tension. The cam disc is adapted to rotate beneath the roller 122 and thus raise and lower said roller, and consequently the thread guide 82, thus to vary the position of the elastic thread on the driving cone 62, and, consequently, the tension of the rubber thread. The weight of the arm 118 and associated parts is adapted to maintain the roller 122 in engagement with the cam profile of the pattern disc 124, although it is obvious that if the weight is insufficient, a spring, not shown, can be utilized for this purpose.

The rotation of the pattern disc 124 is controlled by a tension governing mechanism carried by the depending arm 130 of the

bracket 102. A horizontal stud shaft 132 is fixed at one end to the lower portion of said arm 130 and extends forwardly therefrom. A chain-sprocket 134 is disposed at the free end of said shaft and is rotatable thereon under the frictional restraint of a leaf spring 136 carried by the end of said shaft and bearing upon said sprocket. A ratchet wheel 138 of the same diameter as said pattern disc 124 is fixed to the hub 140 of and is rotatable with said sprocket at the inner end of said shaft. Said pattern disc is disposed between said sprocket and ratchet wheel and is loosely mounted on the hub 140 of said sprocket so that the sprocket can rotate independently of said disc. Said pattern disc is held against rotation in a backward or clockwise direction, Fig. 8, by the engagement of a spring finger 142 with the teeth 144 on the periphery of said disc. Said spring finger is fixed to an horizontally extended rod 146 disposed above the pattern disc and ratchet wheel and fixed to the depending arm of the support bracket 102. The ratchet wheel 138 is similarly secured against backward or clockwise movement by a gravity-operated pawl 148 which is journaled on said rod 146 and is arranged to engage the teeth of said ratchet. Said ratchet wheel 138 and the sprocket 134 are adapted 30 to be advanced one tooth for each revolution of the needle cylinder. To this end, a cam block 150 having an upper cam face 152, see Fig. 1, is secured to one of the depending arms 154 of the take up frame, which frame is carried by and is rotatable with the needle cylinder as is common in the art. An arm 156, see Figs. 8 and 9, is pivoted intermediate its ends on the end of the stud shaft 132 opposite said depending arm 130. A spring 160 is connected with the left hand end of said lever 156 and with a bracket 162 carried by the frame 102 to maintain the other end of said arm in a depressed position as shown in Fig. 8. Said latter end of said arm is provided 40 with a pin 164 which extends inwardly beneath the cam ring 20 and has a roller 166 thereon which is adapted to be engaged by the cam face of the cam block 150 at each revolution of the needle cylinder for the purpose of raising said arm 156. Said arm 156 is provided with an outwardly-extended pin 168 which carries a pawl 170 which is adapted to engage the teeth of the ratchet wheel 138 thus to advance said wheel and consequently 50 the sprocket 134 one tooth at each reciprocation of the arm 156. A spring 172 is connected with said pawl 170 and with the frame 102 whereby to hold the pawl yieldingly in engagement with the teeth of the ratchet wheel. Said pin 168 is also provided with a second pawl 174 which is journaled thereon and which is adapted to engage the teeth of the pattern disc 124. Said ratchet, however, is 60 adapted normally to be held out of driving engagement with the pattern disc except when it is desired to change the tension of the rubber thread. The control of the pawl 174 and, consequently, the tension of the rubber thread, is effected through a pattern chain 176 which is passed around the sprocket 134 and is advanced a small amount for each revolution of the needle cylinder by the ratchet wheel 138 and its pawl 170. The pattern chain is adapted to control the driving engagement between the pawl 174 and the pattern disc 124. To this end, selected links of the pattern chain are higher than others or are provided with raised projections 70 75 80 85 90 95 100 105 110 115 120 125 130 of the chain. An arm 180 is pivotally mounted on the pin 146 and overlies the sprocket 134 and the chain thereon. Said arm is provided with a depending projection or wiper pin 182 which has a tapered lower face 184. Said wiper pin is adapted to be out of contact with the low links of the chain so that such links can pass thereunder without operating the arm 180. The high links or projections 178 of the chain, however, are adapted to engage said wiper pin and raise the arm 180 thus to free the pawl 174 for engagement with the pattern disc. The arm 180 is provided with a downwardly extended rod 186 which is disposed at one side of the pawl 174 and in front of a lateral projection or pin 188 thereof and is adapted normally to serve as an abutment for said pin and prevent the pawl from engaging the teeth of the pattern disc. When, however, the arm 180 is raised by the high links of the chain, the rod 186 is moved away from the pawl thus to permit it to engage with the pattern disc so that as said arm 156 is reciprocated to move the pattern chain, it also slowly advances the pattern disc. When a high link passes from under the arm 180, the arm drops and moves the pawl 174 out of engagement with the pattern disc which consequently remains in set position until it is again actuated. No attempt has been made to show in the drawings the precise number or relation of the high links. A sufficient number will be used. A spring 190 is connected with the pawl 174 and a supporting arm 192 extended from the pin 168 to urge the pawl constantly toward the pattern disc and also to hold the arm 184 in normal elevated position. A leaf spring 194 is fixed to the pin 146 and engages a lateral projection 196 of the arm 180 to return the arm to normal position after a high link 178 has passed thereunder.

With this arrangement, it is seen that the position of the elastic rubber thread between the feed cones is governed by the cam profile carried by the pattern disc so that the tension of the rubber thread and, consequently, the shape imparted to the garment is automatically varied in accordance with the pattern.

A second chain 200 (Fig. 1) and its con-

trolled mechanism 202, of usual construction and arrangement, are utilized to change the stitch from say, a plain rib stitch to a half-cardigan stitch for forming the welt top and bottom, not shown, of the garment of Fig. 11, which welt preferably is knitted without a change in shape.

The machine here shown is adapted for knitting four courses of yarn for each revolution of the needle cylinder and for inlaying elastic rubber thread in each alternate yarn course.

10 If one of the rubber thread feeding mechanisms is disabled or removed or but one used then the rubber thread will be inlaid in every fourth yarn course. Consequently, by providing a sufficient number of

15 yarn feeds, and cams to form the stitch at each yarn feed, and a suitable number of elastic thread feeding mechanisms I am enabled to knit and shape an elastic garment

20 very rapidly and to inlay the thread in every course or in such courses as may be desired, and to obtain a garment of any desired shape and degree of compressional effect.

25 It should be noted that the rubber thread is supplied to the feed and tension cones at "ease" or under no other tension than that caused by the weight of the unsupported length thereof between the skein of thread

30 and the cones, which length is always the same. In Fig. 12, the rubber thread T is drawn from a skein contained in a can 204

stationarily supported on the floor beside the machine. The thread extends upwardly and

35 freely through a guide 206 and thence horizontally and freely through a second guide 208 and thence downward to the feed and tension cones. The length of thread is thus constant and the weight of the dependent

40 lengths is so slight that the thread passes to the cones at ease or at most under a trivial tension, which, is constant.

45 It is important to supply the rubber thread to the cones under constant unvarying conditions for, if the tension of the thread before the cones varies, the tension of the thread between the cones and needles will also vary from the tension detained by the cones and thus nullify the purpose of the tension mechanism and, at least, produce a

50 fabric which is uneven or irregular in shape. It will therefore be apparent that apparatus wherein the rubber thread is subjected to uncontrolled or changing forces before it gets to the tension mechanism cannot produce a

55 fabric of smooth and regular appearance.

The knurled faces of the feed cones 72 and 76 are of considerable importance and were arrived at only after a relatively large amount of experimentation. By having the faces of the cones knurled, the grip of the cones on the elastic thread not only is made positive but thread knots or bunches are positively fed through the bite of the cones since the bunches and knots occupy the re-

cesses in the knurled faces. It is found that with smooth faced cones, the bunches and knots will not always pass through but will stay in front of the cones and the thread will stretch and finally break. This trouble does not appear with knurled cones.

10 The construction may be otherwise modified without departing from the spirit of the invention.

The term "rubber thread" as herein employed is intended to include a single elastic strand as well as two or more strands united to form a thread.

I claim:

1. The combination in a knitting machine, 80 of a stationarily-supported frame, a rotary needle cylinder supported by said frame, means fixed to said frame for feeding an elastic thread to the rotary needle cylinder under variable tensions and including means to vary the tension of the elastic thread, pattern mechanism fixed to said frame, means rotatable with said needle cylinder for operating said stationarily-supported pattern mechanism, and means constantly extended between said pattern mechanism and tension-varying means and controlled by said pattern mechanism for controlling said tension-varying means.

2. The combination in a knitting machine, 95 of a rotary needle cylinder, stationarily-supported means to feed elastic thread at a variable tension to the needles including a pair of thread-driving cones fixed against axial displacement and disposed beside and adjacent the rotary needle cylinder, driving means for at least one of said cones arranged to drive it constantly at a fixed speed, a thread guide disposed in front and movable lengthwise of said cones, whereby to vary the engaging position of the thread with the cones and consequently the tension of the thread, 100 stationarily-supported pattern mechanism, means rotatable with said cylinder for operating said pattern mechanism, and means constantly extended between said pattern mechanism and said thread guide and controlled by said pattern mechanism for moving said thread guide lengthwise of said cones for varying the tension of the rubber thread.

3. The combination with a circular knitting machine and its rotary needle cylinder and the needles therein, of means to feed an elastic thread under variable tension to the needles including a pair of vertical cones 110 disposed beside and adjacent said cylinder, a stationary support for said cones, a gear carried by one of said cones in mesh with the needles of said cylinder, whereby the cone is driven by said needles, a thread guide disposed in front and movable lengthwise of both of said cones to vary the engaging position of the thread on said cones and consequently the tension on said thread, means biasing said guide constantly for movement in 115

120

125

130

one direction lengthwise of said cones, and stationarily-supported pattern mechanism having means which is in constant control of the position of said guide regardless of any rotated position of said cylinder and which supports said thread guide against the action of said biasing means.

4. Apparatus for delivering elastic rubber thread under variable tension to a knitting machine including a pair of cooperating feed cones which are coextensive in length, driving means for one only of said cones, the other cone constituting an idler cone, a thread guide movable along the length of both of said cones, and means to move said idler cone toward and away from the other cone and to hold it in set position with respect to said driving cone.

5. Apparatus for delivering elastic rubber thread under variable tension to a knitting machine including a pair of cooperating feed cones which are coextensive in length, driving means for one only of said cones, the other cone constituting an idler cone, a thread guide movable along the length of both of said cones, and means to move said idler cone toward and away from the other cone including a swinging support for the idler cone, and means controlling the position of said support having means to hold said support in set position against movement away from said driving cone.

6. Apparatus for delivering elastic rubber thread under variable tension to a knitting machine including a supporting bracket, a vertical feed cone journalled on said bracket, driving means for said cone, a swinging support carried by said bracket movable toward and away from said cone, a second vertical cone journalled on and extended above said swinging support, said cones being coextensive in height, means including an adjustable stop member controlling the position of said swinging support with respect to said first cone, and a thread guide carried by said bracket independently of and movable lengthwise of both of said cones.

7. Apparatus for delivering elastic rubber thread under variable tension to a knitting machine including a supporting bracket, a pair of cooperating cones journalled on said bracket, driving means for one of said cones, a thread guide movable lengthwise of said cones, yielding means constantly urging said guide for movement toward one end of said cones, and means controlling the position of said guide arranged to hold it in set position against said urging means.

8. The combination with a knitting machine, of apparatus for feeding elastic rubber thread under various predetermined tensions to the knitting machine, whereby to provide a fabric having a variable outline, including thread driving mechanism having means to vary the tension of the thread in a continuous-

ly variable manner, a movable member the position of which determines the tension of the rubber thread and which can be moved in a continuously variable manner, and pattern mechanism controlling the position of said movable member including a rotary pattern disc having means providing a cam the profile of which corresponds with the outline of the knitted fabric, and a follower riding constantly on said cam-profile having a fixed connection with said movable member by which said movable member and follower are caused to move conjointly.

9. The combination with a knitting machine, of apparatus for feeding elastic rubber thread under variable tension to the knitting mechanism whereby to provide a fabric having a variable outline including thread driving mechanism having means to vary the tension of the thread in a continuously variable manner, a movable member the position of which determines the tension of the rubber thread and which can be moved in a continuously variable manner and pattern mechanism controlling the position of said movable member including a rotary pattern disc having a plurality of pin-receiving apertures in one face thereof and pins received in said apertures in cooperative positions forming a cam the profile of which corresponds with the outline of the knitted fabric, and a follower constantly riding on said pins having a fixed connection with said movable member by which said movable member and follower are caused to move conjointly.

10. The combination with a knitting machine, of apparatus for feeding elastic rubber thread under variable tension to the knitting mechanism, whereby to provide a fabric having a variable outline, including thread driving mechanism having means to vary the tension of the thread in a continuously variable manner, a movable member the position of which determines the tension of the rubber thread and which can be moved in a continuously variable manner, and pattern mechanism controlling the position of said movable member including a rotary member providing a cam the profile of which corresponds with the outline of the knitted fabric, a follower riding constantly on said cam-profile having a fixed connection with said movable member by which said movable member and follower are caused to move conjointly, and means including a pattern chain governing the rotation of said rotary member.

11. The combination with a knitting machine, of apparatus for feeding elastic rubber thread under variable tension to the knitting mechanism, whereby to provide a fabric having a variable outline, including thread driving mechanism having means to vary the tension of the thread in a continuously variable manner, a movable member the position of which determines the tension of the rub-

ber thread, and pattern mechanism controlling the position of said movable member including a rotary member providing a cam the profile of which corresponds with the outline of the knitted fabric, a follower riding constantly on said cam-profile having a fixed connection with said movable member by which said movable member and follower are caused to move conjointly, a driving member for said rotary member, a control member governing the driving connection between said driving and rotary members, and a pattern chain controlling said control member.

12. The combination with a knitting machine, of apparatus for feeding elastic rubber thread under variable tension to the knitting mechanism whereby to provide a fabric having a variable outline, including thread driving mechanism having means to vary the tension of the thread in a continuously variable manner a movable member the position of which determines the tension of the rubber thread, and pattern mechanism controlling the position of said movable member including a rotary member providing a cam the profile of which corresponds with the outline of the knotted fabric, a follower riding constantly on said cam-profile having a fixed connection with said movable member by which said movable member and follower are caused to move conjointly, a reciprocatory driving member for said rotary member having a pawl movable into and out of driving engagement with said rotary member, a control member controlling the action of said pawl and a pattern chain governing said control member.

13. The combination with a knitting machine, of apparatus for feeding elastic rubber thread under variable tension to the knitting mechanism, whereby to provide a fabric having a variable outline including thread driving mechanism having means to vary the tension of the thread in a continuously variable manner, a movable member the position of which determines the tension of the rubber thread, and pattern mechanism controlling the position of said movable member including a rotary member providing a cam the profile of which corresponds with the outline of the knitted fabric, a follower riding constantly on said cam-profile having a fixed connection with said movable member by which said movable member and follower are caused to move conjointly, a sprocket, a pattern chain therein, a ratchet wheel driving said sprocket, a reciprocatory member operated by the rotation of the cylinder having a pawl for moving said ratchet wheel step by step, a second pawl for driving said rotary member, and a control member for governing the driving connection between said second pawl and said rotary member disposed in position to be operated by said pattern chain.

14. Apparatus for delivering elastic rubber thread under variable tension to the needles of a knitting machine, whereby to provide a knitted fabric having a variable outline, including thread driving means arranged to vary the tension of the thread in a continuously variable manner, a movable member, the position of which determines the tension of the thread, said member being movable in a continuously variable manner, and a pattern mechanism for controlling the position of said movable member including a bracket, a shaft carried thereby, a toothed pattern disc having means providing a cam profile rotatably supported on said shaft, a follower riding constantly on said cam profile having a fixed connection with said movable member by which said movable member and follower are caused to move conjointly, a sprocket journaled on said shaft, a ratchet wheel on said shaft beside said pattern disc and fixed to said sprocket, a reciprocatory arm for advancing both said disc and ratchet wheel, pawls carried by said arm adapted to engage both said disc and wheel, a control lever adapted normally to hold one of said pawls out of driving engagement with said pattern disc, and having a wiper member disposed in position to be engaged by said pattern chain and operated to release said pawl.

15. Apparatus for delivering elastic rubber thread under variable tension to the needles of a knitting machine, whereby to provide a knitted fabric having a variable outline, including thread driving means arranged to vary the tension of the thread in a continuously variable manner, a movable member the position of which determines the tension of the thread, said member being movable in a continuously variable manner, and a pattern mechanism for controlling the position of said movable member including a cam-follower having a fixed connection with said movable member by which said movable member and follower are caused to move conjointly, a cam-member rotatable under said follower in constant engagement therewith, a pattern chain, driving mechanism for said cam-member and chain having provision for driving said chain continuously step-by-step, and means controlled by said chain having control of the drive of said cam-member.

In testimony whereof, I have signed my name to this specification.

RICHARD J. WILKINSON. 120
